RESIDENTIAL DWELLING

Paul V. Frakes, Williamsport, Pa., assignor to The Gazer Corporation, Williamsport, Pa.

Filed Jan. 28, 1970, Ser. No. 21,124

Term of patent 14 years

Int. Cl. D25—03

U.S. Cl. D13—1

FIGS. 1, 2 and 3 are perspective views showing all sides of a residential dwelling showing my design.

The broken lines showing the steps and entrance-way are for illustrative purposes only and form no part of the claim.

I claim:

The ornamental design of a residential dwelling, substantially as shown and described.
